COMBINATION LOCK

Thomas J. Gray, Milwaukee, Wis.

Application July 19, 1940, Serial No. 346,244

2 Claims. (Cl. 70—446)

This invention relates to combination locks.

One object of the present invention is to provide a combination lock so constructed that an authorized user may readily find a lost or forgotten combination.

Another object is to provide a combination lock in which the combination may be readily changed and in which a lost or forgotten combination may be readily found but only by an authorized user.

Another object is to provide an improved combination lock which may be opened by manipulation of a plurality of independently operable control elements into predetermined positions.

Another object is to provide in a combination lock indexing mechanism for the accurate positioning of each tumbler.

Another object is to provide a combination lock which may be readily operated in total darkness.

Another object is to structurally combine a receptacle and combination lock for controlling access thereto.

Other more specific objects and advantages will appear from the following description of a combination lock constructed in accordance with the present invention.

In the accompanying drawings:

Figure 1 is a view, partly in vertical section and partly in side elevation, of a combination lock embodying the present invention and shown structurally combined with a receptacle controlled thereby.

Fig. 2 is a front elevation, partly in section, of the combined receptacle and lock shown in Fig. 1.

Fig. 3 is a sectional view taken substantially along the line 3—3 of Fig. 1.

Fig. 4 is a vertical sectional view taken substantially along the line 4—4 of Fig. 2 on a larger scale.

Figs. 5 and 6 are horizontal sectional views taken substantially along the lines 5—5 and 6—6, respectively, of Fig. 4.

Fig. 7 is an exploded view of a tumbler assembly shown in Figs. 4 and 6.

Fig. 8 is an exploded view of a cam assembly shown in Fig. 4.

Fig. 9 is a horizontal sectional view taken substantially along the line 9—9 of Fig. 4.

Fig. 10 is a face view of one of the several separator plates shown in Fig. 4.

Fig. 11 is a front elevation of my improved combination lock embodied in a padlock.

The combination lock selected for illustration is shown in Figs. 1, 2 and 3 structurally combined with a receptacle in a manner to prevent

unauthorized access to the receptacle. The combined unit comprises a cylindrical housing 10 having an integral partition 11 which forms the bottom of a receptacle or depository 12 and separates the latter from a lower compartment 13, which houses the lock.

The receptacle 12 is closed at its upper end by an appropriate removable cover 14 having a pair of depending parallel rods 15 which are projectable through the bottom 11 of the receptacle device in a manner hereinafter described to secure the cover in closed position. A disk or spider 16, carried by the rods 15 adjacent their lower ends, provides a false bottom for the receptacle by which the contents of the receptacle may be readily lifted and removed by raising the cover.

Provision is made for removably mounting and anchoring the housing 10 in a manner to prevent unauthorized removal. For this purpose a bracket plate 17 is provided, adapted to be secured to any appropriate stationary object by screws 18 or the like, hidden and rendered inaccessible by the housing 10 when the latter is applied to the bracket. The housing 10 is provided with a plurality of vertically spaced, substantially square bosses 19, each containing a vertical slot 19' at the rear of the housing to receive one of a plurality of upstanding substantially flat hooks 20 stamped up from the body of the bracket plate 17.

One of the hooks 20 is provided with a circular hole 21 adapted to snugly receive a locking disk 22 slidably fitted within a bore 23 formed in the cooperating boss 19. A pin 24 carried by the disk 22 projects rearwardly through a plug 25 in the rear end of the bore 23 and forwardly through the wall of the receptacle 12, the forward end of the pin being provided with a head 26. The head 26 of the pin is preferably engageable in a slot 14' in the rim of the cover 14 to prevent rotation of the cover in its seat in the housing. A spring 27 urges the disk 22 rearwardly toward the plug 25.

The arrangement is such that, as the housing 10 with its bosses 19 is passed downwardly over the hooks 20 toward the position shown in Fig. 1, the rear portion of the pin 24 passes down through a vertical slot 28 (Fig. 3) in the coacting hook 20, and the disk 22 is forced forwardly into the bore 23 by the bevelled upper end 29 of the hook and thereafter rides over the face of the hook until it registers with and enters the hole 21 in the hook with a snap action, the engagement of the disk within this hole preventing removal of the housing from the bracket. A small extension

30 on the bracket plate 17 behind the hook 20 coats with the rear end of the pin 24 to assist in forcing the disk 22 into the forward end of the bore 23 as the boss 19 is positioned and passed downwardly over the coacting hook.

It will thus be noted that it is impossible to remove the housing 10 from the bracket hooks 20 until the disk 22 is withdrawn from the hole 21 in the coacting hook, and this can be accomplished only by a pull applied to the head 26 of the pin, which of course is inaccessible except through the open receptacle, so that so long as the receptacle is closed it cannot be removed from the bracket. It will also be noted that so long as the receptacle is on the bracket the screws 18 which secure the bracket are inaccessible and the bracket cannot therefore be removed from its support. Access to the screws is further prevented by pillars 31 carried by the ends of the bosses 19 at opposite sides of the rear of the 20 housing.

The combination lock for releasably securing the cover 14 of the receptacle 12 in closed position will now be described. The lock is contained within the lower housing compartment 13 and 25 coacts with the rods 15 to secure the cover against unauthorized removal.

In this instance the interior of the compartment 13 is divided by a plurality of horizontal partition disks 32, each threaded upon a central shaft 33 which supports a lower relatively thick closure disk 34. Each of the disks 32 are perforated to accommodate a pair of vertical rods 35 which extend from the partition 11 to the closure disk 34, and each is also slotted to accommodate a vertical cam bar 36 hereinafter described. The central shaft 33 extends downwardly through the partition 11 from a disk 37 above the partition 11 and enters a central boss 38 in the lower closure disk 34 with which it is in screw threaded engagement. The disk 37, and consequently the shaft 33, are releasably retained against rotation by extension of the rods 15 through the disk 37, and the closure disk 34 is retained against rotation by a pin 10' in the housing engaged in a 35 groove 34' in the disk 34.

The uppermost partition disk 32 is separated from the partition 11 by a spacer sleeve 39 on the central shaft 33 and a latch plate 40 is slidably confined therebetween. The latch plate 40 is urged toward the cam bar 36 by a compression spring 41, which bears against an upstanding lug 42 on the plate, the latch plate being guided by slots 43 which coact with the rods 35 for that purpose.

The latch plate 40 is also provided with openings 44 through which the tapered ends 45 of the cover securing rods 15 are projected when the cover 14 is applied to the receptacle 12, and when thus projected the latch plate 40 engages annular grooves 46 in the rods 15 to normally lock the rods against withdrawal. The latch plate 40 is further provided with a relatively shallow slot 47 to accommodate the upper reduced end 36' of the cam bar 36, the latter having an inclined edge portion 48 which, when the bar 36 is elevated, reacts against the base of the slot 47 to force the latch plate 40 toward the right (Figs. 4 and 5) in a manner to disengage the grooves 46 and thereby release the rods 15 and permit removal of the cover 14. A leaf spring 49, confined at one end between the spacer sleeve 39 and the partition 11, and bearing at its other end against a pin 50 on the bar 36, yieldably retains the latter in the depressed position shown in Fig. 4. As in-

15 dicated in Fig. 4 the under side of the partition 11 is cut away to accommodate the compression spring 41, lug 42, leaf spring 49, and bar 36.

In the device shown, the cam bar 36 may be forced upwardly, to retract the latch plate 40 and thereby release the cover 14 and its retainer rods 15, by means which will now be described. The mechanism for this purpose comprises an inclined arcuate cam 51 rotatably seated upon a disk 52 resiliently supported by a coil spring 53 surrounding the central boss 38 on the lower closure disk 34. The disk 52 is slotted to accommodate the reduced lower end 54 of the cam bar 36 and is perforated to accommodate the vertical rods 35 by which it is retained against rotation.

The integral hub 55 of the arcuate cam 51 is provided on its upper face with an annular set of V-shaped teeth 56 which mesh with a mating set of teeth on the under face of a superposed ring 57. Seated upon the ring 57 is a collar 58, substantially like that shown at 73 in Fig. 7, having a circular series of depending lugs 59, which extend through appropriate slots in the ring 57 to form a driving connection therewith, and which also engage the inner periphery of the hub 55 to center the latter. The collar 58 is also provided with a circular series of upstanding lugs 60 for interlocking engagement with lugs 61 projecting radially from the ring shaped head 62 of an operating lever 64 like that of the lever 72 shown in Fig. 7. This assembly of lever 64, collar 58, ring 57, and the hub 55 of cam 51 are centered by and rotatable about a spacer sleeve 63 which also serves as a separator between the lowermost partition disk 32 and the fixed closure disk 34. The lever 64 extends outwardly from the sleeve 63 through the lowermost of a series of slots 65 formed in the wall of the housing 10.

The arrangement is such that when the lever 64 is swung counterclockwise (Fig. 9) the collar 58 and ring 57 are thereby rotated and the coacting teeth 56, between the ring 57 and hub 55, urge the cam 51 to rotate in the same direction. The cam 51 when rotated in that direction reacts against a shoulder 66 on the bar 36 to urge the latter upwardly. However, if the bar 36 is restrained against upward movement, by any of the tumblers hereinafter described or otherwise, the ring 57 and its supporting disk 52 yield downwardly against the pressure of the spring 53 thereby permitting the mating rows of teeth 56 to separate and thus permit the lever 64, collar 58 and ring 57 to swing or rotate with respect to the cam 51. In this way the parts are protected against damage that might otherwise result from forcing or jamming the parts. The arcuate swing of the cam 51 is preferably limited by appropriate stop pins 52' carried by the disk 52.

Provision is preferably made for preventing unauthorized access to the parts just described. This is accomplished by the use of a disk shield 67 supported upon an appropriate annular shoulder provided on the collar 58. This disk 67 is slotted to accommodate the cam bar 36 and the rods 35. Several of such disks 67 are employed in the lock shown, each being spaced from the adjacent partition disk 32 by a fragmentary disk 68 substantially like that shown in Fig. 10. Each fragmentary disk 68 is preferably the same thickness as the adjacent operating lever so as to insure free swinging action of the lever between the adjacent partition disk 32 and shielding disk 67.

The cam bar 36 is guided for vertical movement by appropriate slots formed in the parti-

tion 1 and closure disk 34 in which the upper and lower reduced ends 36 and 54 are closely and slidably engaged. A plurality of slots 69 are provided in the inner edge of the bar 36 are disposed to clear the several tumblers 70 when the bar 36 is in the lower position shown in Fig. 4, which is the position assumed when the lock is in locked position. And the projection of the several tumblers into the slots 69 prevents movement of the bar 36 upwardly into unlocking position.

In the lock shown, each of the several tumblers 70 comprises a rotatable disk having a slot 71 in its periphery adapted to clear the inner edge of the bar 36 in one particular rotative position of the tumbler. Each tumbler is separately actuated and controlled by a lever 72, interlocked in driving relation with a collar 73 (Fig. 7) in the manner hereinabove described. Each collar 73 is rotatably mounted upon a spacer sleeve 74, which constitutes a separator between adjacent partition disks 32, and each collar 73 is seated upon a tumbler disk 70 and has a reduced lower portion 75 having a close rotating fit within a central opening 76 in the tumbler disk to center the latter. Each collar 73 is provided with depending lugs 59 which engage in slots 77 provided in a ring 78 upon which the adjacent tumbler disk 70 rests. Each ring 78 is thus connected to rotate with its associated collar 73. Each ring 78 is rotatable upon the associated spacer sleeve 74 and rests upon one of the partition disks 32. Each ring 78 is provided on its upper face with an annular series of V-shaped teeth 80 which mesh with a mating set of teeth 81 on the bottom of the associated tumbler disk 70.

By the assembly just described, each tumbler 70 may be positively rotated by manipulation of its actuating lever 72 to accurately align the slot 71 in the tumbler with the edge of the cam bar 36, and when the slots 71 in all of the tumblers are thus aligned the cam bar 36 may be elevated in the manner hereinabove described to release or open the lock.

In order to guide one in rotatably adjusting each tumbler to the position desired, each tumbler 70 is preferably provided with an indexing mechanism which, in the lock shown, comprises a peripheral series of V-shaped ratchet teeth 82 with which a pair of pawls 83 coat to accurately position the tumbler in its several rotative positions. As indicated particularly in Fig. 6, each pawl shown is rockably supported at one end on one of the rods 35 and carries at its other end a pin 84 adapted to engage between successive teeth of the tumbler. The pins 84 of both pawls are yieldably urged toward the teeth by appropriate spring leaves 85, each supported at one end upon one of the rods 35 and bearing at its other end against the interior of the housing 10. Actuation of the lever 72 thus effects step-by-step rotation of its associated tumbler, and the clicking sound of the pins 84 against the teeth provides an audible indication of the advance of the tumbler from one position to the next. This arrangement, together with appropriate scale markings 86 on the exterior of the housing 10, corresponding to successive positions of each tumbler and its actuating lever 72, are of great assistance in adjusting the various tumblers to the positions desired.

In this instance an arrow 87, or other appropriate mark, on each tumbler lever 72 is positioned to register with one of the line markings 75 tumblers.

of the scale 86 in each rotative position of the tumbler and its lever. It will be noted that in the lock shown, the length of each slot 65 is such as to permit each lever 72 to swing through thirteen positions numbered from "0" to "12" successively. It will of course be understood that when any particular one of the five tumblers shown is in a position such that its slot 71 is aligned with the edge of the cam bar 36, its actuating lever 72 may be in any particular one of the thirteen positions just mentioned, and the particular positions of the five levers 72, which will align the slots 71 of their respective tumblers with the edge of the bar 36, constitutes the particular combination which will permit releasing or opening of the lock.

Provision is made for varying this particular combination at the will of the user. This is made possible by the inclusion of an adjustable connection between each lever 72 and its associated tumbler 70 which will permit relative rotative adjustment therebetween, and in the lock shown the coacting rows of V-shaped teeth 80 and 81 between each ring 78 and tumbler 70 provide such a connection. These rows of teeth are normally securely restrained against separation, because each assembly of ring 78, tumbler 70, and collar 73 is confined between successive partition disks 32 which are normally held against separation in a manner about to be described, but which may be released to permit separation of the teeth and consequent rotative adjustment between any ring 78 and tumbler 70.

Mechanism for thus releasably retaining the several partition disks 32 against separation may of course assume various forms, but in the lock shown, it comprises a centrally disposed cam block 88 formed on the upper face of one of the partition disks 32 and coacting with a pair of diametrically spaced cam blocks 89 formed on the under side of a collar 90 which is rotatable about the shaft 33 and bears against the under side of the uppermost partition disk 32. The collar 90 is actuated and controlled by a lever 91, similar to lever 64. The lever 91 extends outwardly through the uppermost slot 65 in the housing 10 and is interlocked with the collar 90 in exactly the same manner that the levers 64 and 72 are interlocked with their respective collars 58 and 73.

With the lever 91 in the "0" position at one end of its slot 65, the collar 90 assumes the position shown on Fig. 4 in which position the cam blocks 89 bear against the cam block 88 and effect a definite spacing between the two upper partition disks 32 and, when thus arranged, the cam blocks 88 and 89 cooperate with the several spacer sleeves 39, 74, and 63 to positively position all of the partition disks 32 and to eliminate all unnecessary looseness or slack within the several tumbler assemblies included therebetween. By swinging the lever 91 to the other end of its slot, however, the collar 90 is thereby rotated into a position where the cam blocks 89 clear the cam block 88, and all of the several partition disks 32, except the uppermost one, are then free to rise under the lifting thrust of the spring 53 through a distance equal to the thickness of the cam block 88, and all of the partition disks 32 thus become yieldably supported by the spring 53 and any of them may be depressed against the upward thrust of the spring 53. The lever 91 and collar 90 are rotated into the position just described, preparatory to changing the lock combination by relative adjustment between the levers 72 and their respective

This adjustment can be made only when the cam bar 36 is elevated into the lock releasing position. Until thus elevated, the bar 36 engages a slot 93 in a disk 92 carried by the collar 90 and prevents rotation of the latter into the position last described; but when thus elevated, a slot 94 in the bar 36 clears the disk 92 and releases the collar 90 for rotation. Also, when the bar 36 is thus elevated, it engages the notches 71 in the several tumbler disks 70 in a manner to restrain them against rotation, a condition necessary to effect rotative adjustment of their respective handles 72 relative to the tumbler disks.

In the lock shown, the changing of the combination involves the following steps. First, the several levers 72 are set into the several positions corresponding to the then combination, so as to align the slots 71 in the several tumblers with the edge of the bar 36 to thereby clear the bar. Then the bar 36 is elevated into lock releasing position by swinging the lever 64 counter-clockwise (Fig. 9) into the far end of its slot 65, as hereinabove described. This locks the several tumblers against rotation and releases the disk 92, so that the collar 90 can be rotated by manipulation of its lever 91. When the collar 90 has been rotated into a position where the cams 89 clear the cam 88 and thus render the several partition plates 32 relatively vertically moveable, the lock is then in a condition to make possible the adjustment of each tumbler lever 72 relative to its tumbler 70. That is to say, in that condition of the lock each of the several tumblers 70 are locked against rotation by the bar 36, and the levers 72 of any of them may be swung to any new positions desired to obtain the new combination desired, the ring 78 beneath each tumbler 70 being free to yield downwardly with its supporting disk 32 in a manner to permit the mating sets of teeth 80 and 81 to clear each other and thus permit the associated lever 72, collar 73, and ring 78 to rotate with respect to associated tumbler 70. When the new combination has thus been established, the lever 91 is finally returned to its initial position, thereby rotating the collar 90 back to the position shown in Fig. 4, in which position the cams 89 again bear against the cam 88 and again render the several partition disks 32 immovable. The new combination is thus fixed.

Provision is also made in the lock shown for finding a forgotten or lost combination preferably by use of a formula, schedule, or chart peculiar to the particular lock and known only to the owner of the lock. This provision is of great importance in the use of a lock of the type described wherein so many different combinations are available and wherein the combination may be so readily changed from time to time.

In the lock shown, this is accomplished in the following manner. A series of vertically aligned perforations 95 are provided in the several partition disks 32, shield disks 67, and fragmentary disks 68, and also in the disk 52 and closure disk 34, these perforations being relatively arranged to permit threading a straight narrow instrument, such as a wire needle, therethrough. One and preferably two perforations 96 are provided in each of the tumbler disks 70, so positioned that one or the other may be brought into alignment with the aligned perforations 95 in the non-rotating disks. A needle 97 for this purpose is also provided which, for convenience, is housed within one of the hollow pillars 31 and carried by a removable plug 98, screw threaded into the upper end of the latter.

To find a lost combination, all of the tumbler levers 72 are positioned in the "0" position on the scale 86, and the end of the needle 97, removed from the pillar 31, is projected upwardly through the several aligned perforations 95, each tumbler disk being in turn rotatably advanced step by step by advance of its lever 72 from the zero position, until one of the perforations 96 therein has been aligned and the needle 97 projected upwardly through all of the tumblers. By this method the needle of course serves as a guide in bringing all of the tumblers into certain predetermined positions with the slot 71 of each tumbler either coincident with or a predetermined distance away from the edge of the bar 36, dependent upon the position of the perforation 96 with respect to the slot 71 in each particular tumbler.

Thereafter, by the use of a table based upon the definite positional relation between the perforations 96 and slot 71 in each of the tumblers of the particular lock, it becomes a simple matter to compute how many steps each tumbler must be turned from the position established by the needle 97 in order to align the slot 71 of each tumbler with the bar 36, and in each instance that number of steps corresponds to the number of points on the scale 86 through which the lever 72 of each tumbler must be shifted from the position established by the needle in order to align the slots 71 of the several tumblers with the bar 36, and the positions to which the several levers must be thus shifted of course correspond to those of the "lost" combination.

It will be noted that the range of movement of each of the several levers 72 is limited to the thirteen positions "0" to "12" on the scale 86, all comprised within a limited arc materially less than 180° and, because of this limited range of movement, it is sometimes impossible to bring one of the perforations 96 in a tumbler disk within the range of the projected needle. Because of this, two perforations 95 are placed in each tumbler disc in such positions that, if one cannot be brought into the range of the needle the other can. In the lock shown, the two perforations 96 in each tumbler are spaced apart an arcuate distance, measured in degrees, equal to the arcuate swing of the lever 72 or, in other words, the two perforations 96 are spanned by a series of thirteen teeth 82 on the tumbler which corresponds in number to the thirteen lever positions represented by the thirteen markings on the scale 86.

With the two perforations 96 thus spaced, it makes little practical difference through which of them the needle is entered in searching for the "lost" combination. For instance, after the needle has been entered through one of the perforations 96 and the chart and computations for that particular tumbler indicate that its lever 72 should be advanced in one direction a certain number of steps, the limited range of movement of the lever may or may not permit such advance, dependent upon which of the two holes 96 had been entered by the needle. If it does permit such advance, such advance will bring the lever into its position in the "lost" combination; if not, retraction of the lever in the opposite direction through a number of steps, equal to thirteen minus the number of steps in the prescribed advance, will bring the lever into its position in the "lost" combination.

It will thus be noted that in the event that the particular combination of lever positions that is

required to release the lock should be forgotten, it may be readily found by the use of the needle and chart associated with that particular lock in the manner above described.

It will also be noted that without knowledge of the particular combination, it is impossible to open the lock, because to do so requires that all five tumblers 70 must be positioned with their slots 71 in alignment with the bar 36 before the latter can be elevated to retract or release the latch plate 49, and all of the tumblers and the latch plate are hidden from view and are absolutely inaccessible. Of the thirteen possible positions for each of the five levers 72, there is only one position of each which will so position its connected tumbler as to align the slot 71 thereof with the bar 36. And this particular position of each of the five levers 72 cannot be ascertained by experiment but only by the method and means above described requiring special knowledge of the particular lock.

In order to baffle unauthorized effort to open the lock by trial or experiment, the lower edges of the slots 69 in the bar 36 are cut away to permit limited upward movement of the bar 36 when the slots 71 of the several tumblers are not aligned therewith, and also to form shallow shoulders 99 adapted to enter between successive teeth 82 of the adjacent tumblers and thereby lock all of the tumblers against rotation when the bar is thus elevated. It is of course understood that this limited upward movement of the bar is insufficient to release the lock and, when thus elevated, the bar locks all of the tumblers against rotation and thus prevents attempted adjustment thereof in an effort to align their slots 71 with the bar.

It will thus be noted that a lock has been provided which is proof against opening except by one having knowledge of the particular combination of lever positions necessary to effect opening, a lock in which the combination may be readily varied at will, and in which a forgotten combination may be readily discovered by one possessing the formula peculiar to the particular lock.

A lock having these characteristics has particular utility when structurally combined with a receptacle in the manner described in that it makes possible the private use of the receptacle by sev-

eral individuals, each to the exclusion of the others, since each may use a particular combination not known to the others. Moreover, a receptacle combined with a lock of the character described may be used as a medium for transmitting private papers or valuable articles from one individual to another, by depositing the item in the receptacle, setting the lock for any particular combination, and giving to the recipient knowledge of that combination so as to render the item available to him. After such a transaction has been completed, the combination can be readily changed to prevent further access to the receptacle.

15 The lock shown in Fig. 11 is identical with that hereinabove described except that it is embodied in a padlock having a conventional hasp 100 having legs which correspond structurally and functionally with the rods 15 hereinabove mentioned.

20 Various changes may be made in the embodiment of the invention hereinabove specifically described without departing from or sacrificing the advantages of the invention as defined in the appended claims.

25 I claim:

1. In a combination lock the combination of a member moveable to release the lock, a plurality of tumblers associated therewith to control lock releasing movement thereof, tumbler actuating means moveable into a particular combination of positions to permit lock releasing movement of said member, and means effective during locked condition of the lock for ascertaining the particular combination of positions of said actuating means which will permit lock releasing movement of said member.

30 2. In a combination lock the combination of a member moveable to release the lock, a plurality of tumblers associated therewith to control lock releasing movement of said member, tumbler actuating means moveable into a particular combination of positions to permit lock releasing movement of said member, and additional means effective during locked condition of the lock for positioning said tumblers in predetermined positions without regard to the positions of said actuating means.

35 THOMAS J. GRAY.
